DESIGN FOR A COMBINED ADVERTISING DEVICE, CIGAR LIGHTER, RADIO, AND CLOCK

Alfred J. Cooper, Cleveland, Ohio

Application August 8, 1939, Serial No. 86,530

Term of patent 3½ years

To all whom it may concern:

Be it known that I, Alfred J. Cooper, a citizen of the United States, residing at Cleveland, county of Cuyahoga, and State of Ohio, have invented a new, original, and ornamental Design for a Combined Advertising Device, Cigar Lighter, Radio, and Clock, of which the following is a specification, reference being had to the accompanying drawing, forming a part thereof.

Figure 1 is a front perspective view of a combined advertising device, cigar lighter, radio, and clock, showing my new design, and

Figure 2 is a rear elevational view thereof.

I claim:

The ornamental design for a combined advertising device, cigar lighter, radio, and clock, substantially as shown.

ALFRED J. COOPER.
